LOGAN A. BECKER AND JOHN M. MUNSON, OF LAKWOOD, OHIO, ASSIGNEES TO THE DOBECKMUN COMPANY, OF CLEVELAND, OHIO, A CORPORATION OF OHIO

PROCESS OF MANUFACTURING CONTAINERS

Application filed October 13, 1930. Serial No. 488,200.

The present invention relates to method of making bags, containers or the like, and particularly bags provided with inwardly folded or bellows-like side portions to make what is known in the art as a square bag.

The invention comprises a new form of bag construction of the type referred to and to the steps employed in the manufacture of such bags, as will be more fully set forth and described herein. One of the objects of the invention is to construct a square bag in which the closure flaps are formed as part of the top and bottom panels of the bag respectively, these flaps extending beyond the body of the bag and folded against the bag, one to provide the permanent closure at one end of the bag and the other to provide the closure flap at the mouth of the bag.

The invention and the advantages thereof will be apparent from the description given herein, it being understood that changes and modifications may be made in the details of the invention without departing from the scope thereof.

In the drawings in which the preferred method of manufacturing bags is shown:

Figure 1 is a plan view of a bag showing the manner in which the bag is formed from a sheet or web;

Figure 2 is a plan view of the completed bag;

Figure 3 is a section thereof on the line 3—3 of Figure 2;

Figure 4 is a cross section of the expanded bag;

Figure 5 is an enlarged detail at the open end of the bag;

Figure 6 is an enlarged detail at the closed end of the bag before the folding and sealing operation;

Figure 7 is a similar view after the sealing operation;

Figure 8 is a cross section on the line 8—8 of Figure 7;

Figure 9 is a cross section on the line 9—9 of Figure 7;

Figure 10 is a cross section through the mandrel or form upon which the cutting operation takes place showing the relation of

the formed bag tubing with respect to the mandrel;

Figure 11 is a cross section on the line 11—11 of Figure 10;

Figure 12 is a plan view of a modified form 65 of bag blank;

Figure 13 is a cross section showing the cutting operation; and

Figure 14 is a plan view of the completed bag, looking at the front or unseamed panel 60 of the bag.

It is the purpose of the invention to construct a square bag having plicated or bellows-like side plies, from a continuous web of sheet material. While the invention is originally intended for use in the manufacture of bags or containers from regenerated cellulose sheeting, such as known by the trade name "Cellophane", the invention is not necessarily limited to the use of such material, and it will be understood that any sheet material may be employed.

The completed container is formed from a single sheet having an upper or central panel 1, and a rear panel 2, in which is located the longitudinal adhesive seam 3 along which the edges of the sheet are adhesively joined to complete the tubular form of the bag. In the side panels 5 are located the inwardly extending bellows-like folds 6 which permit 80 the bag to open as shown in Figure 4.

The closed end of the bag is provided with the flap 8, which is composed of the two extensions on the sides of the blank. The end of the tube is folded along the transverse line 10, and the flap is secured by an adhesive such as shown at 12. The corner of the bag at the closed end is therefore composed of eight plies or thicknesses of the material, as shown in Figure 8, and is therefore very strong. 90 The corners are also sift proof, as will be seen by an inspection of that view.

The open end of the bag is formed with the forwardly extending flap 15, which is a continuation of the central panel 1.

The blank is so formed that successive bags may be cut from a continuous strip or web of the material without waste, it being observed that the central panel 1 is offset in the same direction with respect to the two wings 2a and 100

^{2b} which constitute the rear panel. Each of the wings ^{2a} or ^{2b} is connected to the central panel by cuts 18, which extend in the general longitudinal direction of the web, and are preferably oblique thereto, as shown. At the point where these cuts meet a forward end cut, inwardly curved extensions 19 are provided to give reentrant or bay-like formations at the corners of the container mouth. This makes a very strong corner, and one which will not tear even when subjected to considerable stress in the filling operations. This reentrant or bay-like formation 19 is a valuable feature of the bag construction, as it not only strengthens the corner of the bag, but due to its reentrant formation, accurate register of the transverse cuts with the end of the line 18 is not necessary, and it is indeed desirable to extend the transverse cuts into the bay like formations so as to insure positive cutting. Were the angle of the bag mouth not provided with the reentrant formations, exposed material might be notched in the severing operation which would start a tear in the material.

In the manufacture of the new form of bag, and by the process shown and described, the continuous web of stock is folded longitudinally as it is passed through a tube or bag forming machine of any of the usual types. During the tube forming operation the inwardly extending plicated sides are also fabricated, in the manner well known and understood in the art.

Referring to the blank shown in Figure 1, the successive lines of folds *a*, *b* and *c* indicate respectively, the fold between the central panel and the side panel, the fold *b* in the side panel, and the fold between the side panel and the rear panel. The transverse cuts which sever the blanks from the web are indicated at *d* and *e*, the former being located in front of the latter, and, respectively, forming the ends of the rear and central panels.

It will be observed that the line of the outside fold *c* intersects the lines 18 at some intermediate point. At the points where the line of inside fold *a* intersects the cut *e*, the blank is cut out along a recessed or curved line 20, one of the purposes of which is to provide a recess or bay at the corners of the bag where the side panel meets the central panel. This also has a purpose and function in connection with the cutting of the blanks from the web as will now be described.

The slits 18 and 20 are made in the web of material prior to the folding or tube forming operation, and are made by any suitable means such as slitting knives which are brought into contact with the web as it passes from a supply to the tube forming mechanism, all of which are well understood in the art, and need not be described or shown.

After the tube is formed and sealed along

the longitudinal seam 3 it is ready for the cutting operation, and for this purpose the tube is fed over a mandrel or cutting block 25. For the purpose of illustrating the invention, the block is shown in Figure 10 as located immediately adjacent the rear panel 2, and fitting within the lower side of the bellows folds between the folds *b* and *c*. This brings the central panel 1 and the two overlying folds of the two side panels on the same side of the mandrel or cutting block. A knife 26 is employed to cut the thicknesses of material above the mandrel on the line *e*, and the knife 27 to cut the single thickness of material below the mandrel on the line *d*, grooves 28 being located in the mandrel to receive the knives. These knives are out of register as shown to secure the non-registering cuts, which locate the central and rear panel offset with respect to each other.

It will now be noted that the slits 18 extend around the edge of the mandrel. The slits 20 overlie the edge of the mandrel and are located over one end of each of the slits 18. This is found necessary as the mandrel is of appreciable thickness, and as it is impossible to cut upon or around the edges thereof, the said slits supplement the knives, and make possible a complete severing of the blank. An advantage of the curved formations at 19 and at the ends of the slits 20 will now be apparent, as it is possible to secure perfect and satisfactory severing of the successive blanks, without the necessity of positive and accurate alignment of the cutting knives with the slits. For example, as shown at *X* in Figure 1, the ends of the slits 20 may extend beyond the transverse cuts *e*, and the ends of the slits 18 may extend beyond the cuts *d*. In either case the notches *X* will occur in the folded and sealed ends of the bag, and no tear can be started at these points. Likewise the ends of the transverse cuts are shown extending beyond the slits without injurious effects.

By the invention shown and described herein, it is possible to utilize the non-registering cut-off method for cutting blanks from a continuous web of material in the manufacture of plicated or bellows folded bags. The specific means for carrying out the invention as shown and described is not essential as other or equivalent means may be employed. The reciprocating knives 26 and 27 are employed as they seem to be best suited for the fabrication of bags of "Cellophane", but with other materials such as paper or the like, other well known severing instrumentalities may be employed.

After the blanks are severed from the leading end of the tube, the forwardly extending end of the bag is folded over on the transverse line 10, and the bag is completed.

Instead of having the seam in the shorter panel of the bag as described, the invention

also contemplates the location of the seam in the longer panel. This variation is shown in Figures 12 to 14 inclusive, which also illustrate that the relative positions of the mandrel, the seam and the bellows folds may be changed as desired.

In the form of the invention shown in these later views, the central panel is indicated at 30, the side panels at 31, and the rear or seamed panel at 32, composed of the two wings 32^a and 32^b offset from the central panel but in the opposite direction from that shown in Figure 1.

It will be observed that in this form, the inner fold a' intersects the diagonal slit 18^a and that that slit is placed in the opposite direction from that occupied by the slits 18. The reentrant slits 20^a are located on the outside of the side panels and are intersected by the fold c'. The fold 10^a is the same as before, it being noted, however, that the permanent closure flap is formed by the extension 35 of the central panel 30 rather than by the side wings as in the preferred form. In the finished bag the seam is located on the panel having the extending flap at the bag mouth.

To sever the blank from the web, the position of the mandrel is reversed as indicated above, the tube being threaded over the mandrel adjacent the unseamed panel. The upper knife 26 cuts the seamed panel and the bellows folds, while the lower knife 27 cuts the unseamed panel only. The parts may be reversed, with the same results.

It is also possible to change the relative location of the mandrel with respect to the bellows folds and cuts in the same relationship, but this would give an inferior bag construction.

The invention consists in the new and novel method of making a square bag with the plicated folds along the side panels. It will be apparent that changes and improvements may be made in specific embodiments of the invention, all within the scope thereof. While a central seam is indicated in both forms of the invention, the seam may be shifted by suitable off center slitting and folding.

What we claim is:

1. The process of manufacturing square bags comprising providing a web of material with transversely aligned slits arranged with a pair of reentrant slits on opposite sides of the central line of the web, and other slits extending in the general longitudinal direction of the web arranged between the first named slits and the edges of the web, folding the web longitudinally to form bellows like sides for the bag, the fold lines of said bellows on each side of the bag intersecting the reentrant slits and the longitudinal slits, and severing a blank from the web by transverse non-registering cuts on opposite sides of the tube, one of said cuts intersecting all of the

slits, and the other connecting the ends of the longitudinal slits.

2. The process of manufacturing square bags comprising providing a web of material with pairs of slits extending in a general longitudinal direction with respect to the web, located on opposite sides of the central line of the web, forming second slits in the web extending in a general transverse direction with respect thereto, forming a tube from the web with inwardly extending longitudinal bellows folds on either side of the web, the outer of said folds intersecting the respective slits, and severing a blank from the web by non-registering cuts on opposite sides of the tube in the region of said slits.

3. The process of manufacturing square bags, comprising providing a web of material with pairs of slits extending in a general longitudinal direction with respect to the web, located on opposite sides of the central line of the web, forming second slits in the web extending in a general transverse direction with respect thereto, said second slits being recessed, forming a tube from the web with inwardly extending longitudinal bellows folds on either side of the web, the outer of said folds intersecting the respective slits, and severing a blank from the web by non-registering cuts on opposite sides of the tube in the region of said slits.

4. The process of manufacturing square bags, comprising providing a web of material with pairs of oblique slits extending in a general longitudinal direction with respect to the web, located on opposite sides of the central line of the web, forming second slits in the web extending in a general transverse direction with respect thereto, forming a tube from the web with inwardly extending longitudinal bellows folds on either side of the web, the outer of said folds intersecting the respective slits, and severing a blank from the web by non-registering cuts on opposite sides of the tube in the region of said slits.

5. The process of manufacturing square bags, comprising providing a web of material with pairs of oblique slits extending in a general longitudinal direction with respect to the web, located on opposite sides of the central line of the web, forming second slits in the web extending in a general transverse direction with respect thereto, said second slits being recessed, forming a tube from the web with inwardly extending longitudinal bellows folds on either side of the web, said folds intersecting the slits, and severing a blank from the web by non-registering cuts on opposite sides of the tube in the region of said slits.

6. The process of manufacturing square bags, comprising providing a web of material with pairs of slits extending in a general longitudinal direction with respect to the web, located on opposite sides of the central

- line of the web, forming second slits in the web extending in a general transverse direction with respect thereto, forming a tube from the web with inwardly extending longitudinal bellows folds on either side of the web, the outer of said folds intersecting the respective slits, and severing a blank from the web by non-registering straight cuts on opposite sides of the tube in the region of said slits.
7. The process of manufacturing square bags, comprising providing a web of material with pairs of slits extending in a general longitudinal direction with respect to the web, located on opposite sides of the central line of the web, forming second slits in the web extending in a general transverse direction with respect thereto, said second slits being recessed, forming a tube from the web with inwardly extending longitudinal bellows folds on either side of the web, the outer of said folds intersecting the respective slits, and severing a blank from the web by non-registering straight cuts on opposite sides of the tube in the region of said slits.
8. The process of manufacturing square bags which comprises the steps of providing a web of material with rows of slits at spaced intervals, each row comprising pairs of slits on either side of the central line of the web, and each pair consisting of a slit extending in the general direction of the web, and a slit extending transversely thereof, forming a tube from the web with double folds which intersect the slits and bringing a transverse slit in register with one end of a longitudinal slit, and cutting the tube by transverse non-registering cuts from opposite directions, the cuts supplementing the slits, to sever a bag from the tube.
9. The process of manufacturing square bags, comprising providing a web of material with pairs of oblique slits extending in a general longitudinal direction with respect to the web, located on opposite sides of the central line of the web, forming second slits in the web extending in a general transverse direction with respect thereto, said second slits being recessed, forming a tube from the web with inwardly extending longitudinal bellows folds on either side of the web, said folds intersecting the slits, and severing a blank from the web by non-registering straight cuts on opposite sides of the tube in the region of said slits.
10. The method of forming a bag from a continuous web, comprising forming rows of slits at spaced intervals along the web, each row of slits comprising pairs on opposite sides of the central line of the web, each pair of slits consisting of a transverse slit and a slit extending in the general direction of the web, folding the web into a tube with longitudinal folds forming bellows sides, the outer of said folds intersecting the slits, and cut-
- ting the tube into individual blanks by non-registering cuts from opposite sides thereof, which supplement the slits to sever the blank from the web.
11. The method of forming a bag from a continuous web, comprising forming rows of slits at spaced intervals along the web, each row of slits comprising pairs on opposite sides of the central line of the web, each pair of slits consisting of a transverse slit and a slit extending in the general direction of the web, each slit having an angular extension, folding the web into a tube with longitudinal folds forming bellows sides, the outer of said folds intersecting the slits, and cutting the tube into individual blanks by non-registering cuts from opposite sides thereof which meet the angular extensions and supplement the slits to sever the blank from the web.
